UNITED STATES PATENT OFFICE.

AARON JACOB SMITH AND FOSTER T. FREDERICK, OF CHICAGO, ILLINOIS; SAID SMITH
ASSIGNOR TO SAID FREDERICK.

SAFETY PIN.

Application filed August 30, 1922. Serial No. 585,138.

To all whom it may concern:

Be it known that we, AARON J. SMITH and FOSTER T. FREDERICK, citizens of the United States, residing, respectively, at Chicago, in the county of Cook and State of Illinois, and at Chicago, in the county of Cook and State of Illinois, have jointly invented certain new and useful Improvements in Safety Pins, of which the following is a specification.

Our invention relates to an improvement in safety pins, and has for its primary object the provision of a safety pin which is locked when in closed position against opening and which cannot readily be opened when in closed position without a combination of movements designed to disengage the free end of the pin from the head and to open it.

Another and further object of our invention is the provision of a safety pin which is primarily adapted for laundry work and at the same time is equally adaptable for any purpose where safety pins may be employed, and particularly for use in fastening children's clothes, in that it is securely locked against opening by the child, or accidental opening either by becoming bent, due to the strain imposed upon the pin by the clothing or other material through which the pin passes, or by the friction of the clothing upon the head of the pin.

Another and further object of our invention is the provision of a safety pin having a larger capacity than is usual for the same length pin in that it can be inserted through more clothing or other articles adapted to be fastened by the pin than is common with pins of this character, in that we provide a spring coil in the rear portion of the body member instead of at the bottom of the pin as is common with pins of this class, so that the body of the pin can readily be passed through the material to a farther extent than is common with the usual form of safety pin, the spring coil also serving to hold the material in place, preventing wear and tear of the material through which the pin passes.

Another and further object of our invention is the provision of a safety pin which can be manufactured cheaply, which is efficient and simple in operation and which is effectually locked against opening even though the pin may be bent, resulting in the

unfastening or loosening of the free end of the pin as is common in pins of this character.

These and further objects of our invention will be more fully and better understood by reference to the accompanying sheet of drawings and in which—

Figure 1 is a side elevational view of our improved safety pin showing the pin in closed position.

Figure 2 is an elevational view partially in section showing the pin in closed position.

Figure 3 is a detailed vertical sectional view on lines 3—3 of Figure 1.

Figure 4 is a detailed side elevational view of the pin head shown in Figure 3.

Figure 5 is a detailed sectional view on lines 5—5 of Figure 1.

Figure 6 is a detailed sectional view on lines 6—6 of Figure 2.

Referring specifically to the drawings and in which like reference characters refer to like parts throughout, a safety pin 10 is shown having a body member composed of 80 spring wire or the like and bent so that a pair of parallel extending portions 11 and 12 are provided, the front portion 12 being the free portion of the pin, having the usual bend 12^a at the bottom thereof, with a coil 13 formed approximately midway intermediate the ends of the rear portion 11 so that an added amount of elasticity is provided in the rear portion 11 of the pin. The upper part 14 of the rear portion 11 is curved until 90 it forms approximately a half circle, terminating at 15 adjacent the free end 16^a of the front portion 12 of the pin. On the curved portion 14 is mounted a head 16, the said head being composed of a thin strip of metal bent so as to provide a flat side wall portion 17 with a similar opposite flat side wall portion 18 with curved marginal edges, the rear side of which engage the upper end of the portion 11, and the front side forms a pocket for the reception of the free end 16^a of the portion 12. A rivet or stud 19 is provided, which extends through the walls 17 and 18 of the head 16 on the inside of the curved portion 14, serving to hold the head 16 in position upon the curved portion 14 of the pin and in limited sliding engagement therewith, so that the head portion 16 can be moved slightly upon the curved portion 14 of the pin, the limit of outward movement being 110

2
determined by the engagement of the stud 19 with the curved portion 14, as shown in Figure 2. Depending from the side wall 17 of the head 16 is a spring portion 20 integral with the wall 17 or secured thereto, as may be found desirable, the spring 20 extending upward and diagonally across the inner space of the head 16 from the lower portion of the wall 17 to the wall 18, where 10 a portion 21 of the spring 20 is bent outwardly and passes through an opening 22 in the wall 17 and has a head 23 formed thereon outside of the wall 17, the spring 20 forming the locking means for holding the head 16 in its lowermost position upon the body of the safety pin by engagement of the portion 21 of the spring 20 with the inside of the curved portion 14 of the pin. Depending from the wall 18 is a lip 24 formed 20 integral with the head portion 16 and which serves as a locking member for the free point 16^a of the pin when the head is in its lowermost or locked position. At the lower portion of the wall 18 is an arcuate shaped recess 25 adapted, when the head of the pin is in its extended position, to allow the free end 16^a of the pin to be disengaged from the pocket in the head 16 and pass outward therefrom into open position shown in Figure 2.

30 The coil 13 on the rear portion of the pin allows the pin to be inserted the full distance through articles or material which is held together by the pin, such as laundry bags or the like, all of the way up to the coil 13, 35 instead of being limited by a coil usually placed at the point 12 on the pin, and providing an additional amount of elasticity in the body of the pin so that when the free end 16^a is disengaged the pin automatically 40 opens.

In operation the device is exceedingly simple but effective and requires a combined movement of the hands, namely, the pulling out of the spring 20 from engagement 45 with the portion 14 by lifting the head 23 in any suitable manner so that the portion 21 of the spring is out of engagement with the portion 14 of the body, and this allows the head 16 to slide outward until the pin 19 is 50 in engagement with the portion 14 of the body of the pin, whereupon, the safety pin is unfastened in the usual manner of safety pins by pressing the free point 16^a inwardly until it can be pushed sidewise through the 55 arcuate recess 25 in the side walls 17 and 18.

When it is desired to close the pin after being inserted through the material, the reverse operation takes place. The free end of the pin is pushed inwardly until it is opposite the arcuate shaped recess 25 and is then inserted against the inner side of the wall 18 between the walls 17 and 18, whereupon the point is released and it passes outwardly into the pocket in the head 16 in the 65 position shown in Figure 2. The head 16 is

thereupon pushed downward until the horizontal portion 21 of the spring is below the curved portion 14, whereupon the spring snaps into place underneath the curved portion of the head, thus holding the head securely in position until the spring is released. As the head 16 is pushed downward the lug 24 is positioned behind the free end or point 16^a of the pin as shown in Figure 1, thus effectually locking the point 16^a of the pin against opening.

In addition to the engagement of the locking lug 24, the upper edge of the arcuate shaped recess 25 is a sufficient distance below the point of the pin when the head 16 is in 80 locked position, so that if for any reason the lug 24 should be destroyed, the head must still be pushed outward in order that the free end 16^a of the pin can be disengaged from the head 16.

While we have described more or less precisely the details of construction, we do not wish to be understood as limiting ourselves thereto, as we contemplate changes in form and the proportion of parts and the substitution of equivalents as circumstances may suggest or render expedient without departing from the spirit or scope of our invention.

We claim:

1. A safety pin comprising in combination a body member having parallel extending side portions with looped portions at each of its ends, one of said side portions terminating adjacent one of said looped portions and forming a point for said pin, a head secured to one of said looped portions and adapted to hold the free end of said body portions in normal closed engagement, the said head having a limited sliding movement upon said body portion and a spring locking member adapted to engage against the inner curved body portion whereby the head is held in locked position.

2. A safety pin comprising in combination a body member having parallel extending side portions with looped portions at each of its ends, one of said side portions terminating adjacent one of said looped portions, forming a point for said pin, a head secured to one of said looped portions and adapted to hold the free end of said body portion in normal closed engagement, the said head having a limited sliding movement upon said body portion, and locking means in said head portion adapted to engage the under side of the curved body portion whereby the head portion is held against movement when the pin is in closed position.

3. A safety pin comprising in combination a body member having parallel extending side portions with looped portions at each of its ends, one of said side portions terminating adjacent one of said looped portions, forming a point for said pin, a head secured to one of said looped portions and adapted

- to hold the free end of said body portion in normal closed engagement, the said head having a limited sliding movement upon said body portion, and a spring secured to said 5 head portions adapted to engage the under side of the curved part of the said body portion, whereby the said head is held in locked engagement when the said pin is closed.
- 10 4. A safety pin comprising in combination a body member having parallel extending side portions with looped portions at each of its ends, one of said side portions terminating adjacent one of said looped portions, forming a point for said pin, a head secured 35 to one of said looped portions and adapted to hold the free end of said body portion in normal closed engagement, the said head having a limited sliding movement upon said body portion, and a spring secured to said 40 head portions adapted to engage the under side of the curved part of the said body portion, whereby the said head is held in locked engagement when the said pin is closed, and a lug secured to said head portion adapted 45 to engage with the rear side of the free part of the said body portion when the head is in locked position upon said body portion.
- 15 5. A safety pin comprising in combination a body member having parallel extending side portions, one of said portions being free and forming a point for said pin, and a head member secured to the other portion and in sliding engagement therewith, the side portion opposite the free portion having 50 a coil intermediate its ends, the said coil extending inward towards the opposite parallel extending side portion.
- 20 6. A safety pin comprising in combination a body member having parallel extending side portions, one of said portions being free and forming a point for said pin, and a head member secured to the other portion and in sliding engagement therewith, the side portion opposite the free portion having 55 a coil intermediate its ends, the said coil extending inward towards the opposite parallel extending side portion.
